United States Patent Office

Des. 231,779
Patented June 11, 1974

231,779

BUILDING STRUCTURE

John D. Cole, 3860 Honey Hill Lane,
Dayton, Ohio 45405

Filed Aug. 14, 1972, Ser. No. 280,595

Term of patent 14 years

Int. Cl. D25—03

U.S. Cl. D13—1 E

FIG-1

FIG-2

FIG-3

FIG-4

FIG. 1 is a perspective view of a building structure showing my new design;

FIG. 2 is a top view thereof;

FIG. 3 is one side view, as viewed on the line 3—3 of FIG. 2; and

FIG. 4 is another side view, as viewed on the line 4—4 of FIG. 2.

I claim:

The ornamental design for a building structure, substantially as shown and described.
